BARREL

George H. Osgood, Tacoma, Wash.

Application February 18, 1931, Serial No. 516,591

3 Claims. (Cl. 217—96)

This invention relates to the construction of barrels, and other similar containers, and has for its objects to provide a barrel which may be shipped and stored in knockdown condition, with 5 other similar nested therewith, thereby permitting a much larger number of barrels to be shipped or stored in any given space; which may be quickly and cheaply assembled as needed for use; which, when thus assembled, presents a 10 smooth surface on its inner and outer faces; which requires no hoops of wood or metal to bind it together; which is of great strength and yet is sufficiently resilient to resist breakage from rough handling; which is substantially as strong 15 in the seams as at other points thereof; which is substantially as strong as and of about one-half the weight of the barrels commonly in use at the present time; which requires no special tools or devices for assembling, closing or sealing; and 20 which will hold its contents securely and adequately protect them from damage.

I attain these and other objects by the devices and arrangements illustrated in the accompanying drawing, in which—

25 Figs. 1 and 2 are enlarged sections showing, respectively, two contiguous edges of two semicylindrical sections of a barrel, separated; Fig. 3 shows them secured together to form the joint or seam of the barrel; Fig. 4 is an end elevation of one such semicylindrical section before being assembled with a complementary section to form a barrel; Fig. 5 is an end view of a nest of such sections ready for storage or shipment; and Fig. 6 is a side elevation of my improved barrel, showing a part of its side broken away to reveal the means of closing the ends thereof.

Similar numerals of reference refer to similar parts throughout the several views.

Referring to the drawing, it will be seen that 40 my improved barrel comprises two arcuate sections, 1 and 2, built up of the usual construction of plywood, in which the grain of the several layers runs at right-angles to that of the contiguous layers, and each having the inner side of one longitudinal edge 3 and the outer side 4 of the other longitudinal edge cut away to the center of the thickness of the plywood (Figs. 1 and 2), for a short distance from said edge, to permit a similar section to be fitted thereto (Fig. 3) 45 to form the two longitudinal joints or seams (Fig. 6) of the barrel. As above stated the edges are cut away in complementary manner to give a wide arcuate or tangential joint between the said parts and to permit the adjacent edges and shoulders to butt against each other. It will be

readily understood from a consideration of Fig. 3 that the strength of the barrel at the seam, thus formed, is substantially the same as at other portions thereof because, as is well understood, the grain of the central layer of plywood extends 60 around the barrel while the grain of the inner and outer layers extends parallel to the axis. Since the central layers of the two sections forming the joint are only partly cut through, it follows that the outer and inner layers are both reinforced against splitting by the uncut portion 65 of the central layers. The outer and inner layers of the barrel, therefore, provide the requisite axial strength and stiffness to the barrel, while the inner layer provides the circumferential 70 strength needed. Also, this plywood construction renders it possible to use staples or other fastening means in the seams which would otherwise be impractical because of their splitting effect on the thin bent wood whose grain would be parallel 75 to the axis of the barrel.

Under usual conditions I prefer to secure the two edges of the sections together by means of staples 5, driven in from the outside and clenched on the inside, but nails, tacks, or other securing 80 means may be adopted if desired.

The ends of the barrel may be closed by solid wood or plywood closure pieces 6, cut to proper size and shape and secured in place by suitable cleats 7, fastened into the inner edge of the barrel. These cleats 7 may be conveniently made 85 from trimmings of the barrel sections 1 and 2 and may be extended entirely around the inner periphery of the barrel, outside of the head 6, or may be made of shorter pieces, spaced apart, as 90 is desired for the particular use to which the barrel is put.

Thus it will be seen that my improved barrel may be shipped and stored in nested or knockdown condition, as indicated in Fig. 5 and, when it 95 is desired to use them, they be assembled by placing two such sections in reversed relative positions and stapling the edges together through the lap joint above described. Such a barrel will expose a smooth surface, both to the outside and 100 the inside; will occupy the least possible space; will add but little weight to the weight of the material being shipped therein; will be strong and stiff and yet resilient; and will stand a great amount of rough handling without injury.

105 Although, in the drawing and in the above description, I have shown and described a barrel constructed of three-ply plywood, it is to be understood that I do not confine myself to any particular number of plies of which such plywood is to 110

be constructed but that there must be at least three such layers. In practice it may be found that five or even more layers will be necessary for barrels designed for particular purposes, but for ordinary use it has been found that threeply construction is most satisfactory. It is, of course, to be understood that the several layers of the plywood are properly cemented or glued together in the usual manner. Also, I have shown and described the barrel as made in two semicylindrical sections 1 and 2, but it is to be understood that I do not wish to limit myself to any particular number of such sections as the barrel could be made in three or four sections without materially affecting its strength, but, again, I find that the semicylindrical construction is most satisfactory. Again, if the knockdown feature of this construction should not be desirable, the barrel may be made in a single section having only one seam.

Having described my invention, what I claim is—

1. A joint between two bodies of wood, each body comprising two layers of wood cemented together to form a single structure, the first or contacting layers each having the grain running at right-angles to the bursting stress on the joint and parallel with each other, said contacting layers being reenforced by the second layers cemented thereto, each to each, said second layers having their grain running parallel with the bursting stress on the joint and parallel with each other; and metallic fastening means passing through the four overlapped layers thus formed and adapted to carry the bursting stress from one second layer to the other second layer and to relieve both said first layers of bursting stress.
2. A joint between two bodies of wood, each body comprising two layers of wood cemented to—

gether to form a single structure, the first or contacting layers being each of substantially one-half the thickness of the second layer and each said first layers having the grain running at right-angles to the bursting stress on the joint and parallel with each other, said contacting layers being reenforced by the second layers cemented thereto, each to each, said second layers having their grain running parallel with the bursting stress on the joint and parallel with each other; and metallic fastening means passing through the four overlapped layers thus formed and adapted to carry the bursting stress from one second layer to the other second layer and to relieve both said first layers of bursting stress.

3. A longitudinal joint between adjacent edges of contiguous portions of a cylindrical wooden barrel, the edges of the portions being complementarily cut away to substantially the central plane to permit them to overlap; each of said overlapped portions comprising two layers of wood cemented together to form a single structure, the first or contacting layers being each of substantially one-half the thickness of the second layer and each said first layers having the grain running at right-angles to the bursting stress on the joint and parallel with each other, said contacting layers being reenforced by the second layers cemented thereto, each to each, said second layers having their grain running parallel with the bursting stress on the joint and parallel with each other; and metallic fastening means passing through the four overlapped layers thus formed and adapted to carry the bursting stress from one second layer to the other second layer and to relieve both said first layers of bursting stress.
